UNITED STATES PATENT OFFICE

JOSEPH F. KASNICKA, OF CICERO, ILLINOIS

DEVICE FOR TREATING AND PREVENTING INSECT BITES

Application filed February 6, 1930. Serial No. 426,268.

In the past it has been customary for sportsmen and other persons who were exposed to the bites of mosquitoes, flies and other insects to saturate their clothing and 5 to coat their skin with various kinds of liquid insectifuge to repel the insects. Such a procedure is obviously inconvenient since it requires the use of some form of an applicator to spread the liquid over the skin and has 10 necessitated the carrying of a supply of liquid which may easily be spilled and lost at times when replacement is exceedingly difficult. The liquids used often contain substances to relieve the stinging sensation in 15 the insect's bites and to prevent swelling and infection of the flesh about the bites.

The primary object of the present invention is to provide a new and improved means for carrying either an insectifuge, a healing 20 agent or both, whereby all of the advantages of a liquid insectifuge are obtained without the danger of loss due to spilling of the liquid.

Another object is to provide a simple, economical article of this character which is 25 easily carried and embodies simple and effective means for containing the insectifuge and for applying it to the various parts of the body.

30 Other objects and advantages will become apparent from the following description and the drawing, in which:

Figure 1 is a perspective view of a device embodying the preferred form of the invention.

Fig. 2 is a central sectional view of the device shown in Fig. 1.

While the invention is susceptible of various modifications and alternative constructions, I have shown in the drawing and will herein describe in detail the preferred embodiment, but it is to be understood that I do not thereby intend to limit the invention to the specific form disclosed, but intend to 40 cover all modifications and alternative constructions falling within the spirit and scope of the invention as expressed in the appended claims.

In the form chosen for disclosure the invention is embodied in a device especially

adapted to be carried in a person's pocket without producing a bulky projection. As illustrated, the device has a metallic ring or band 10 of cylindrical form which defines generally the outline of the device, the width 55 of the band being substantially less than the diameter thereof so that the device as a whole will be comparatively thin and disk-like in character.

On one end or edge the band 10 has an 60 inturned flange 11 which partially closes that end and against the inner side of the flange a resilient pad 12 formed from cloth or some similar material is positioned so as to extend entirely across the aperture defined by the 65 inner edge of the flange 11. The pad 12 serves as an applying means whereby an insectifuge may be rubbed over a person's skin and to supply the pad 12 with a liquid insectifuge, means is positioned within the band 10 in contact with the inner surface of the pad. This 70 means is preferably of such a character that the liquid can not be accidentally lost by spilling and in the present case it comprises a block or body 13 (Fig. 2) of substantially 75 rigid porous material such as wood impregnated with the desired liquid and positioned within the band 10 in contact with the inner surface of the pad. To insure that the block 13 will be completely saturated with the liquid an aperture 14 is formed therethrough.

Due to its substantially rigid character, the body 13 may be formed with one dome-shaped side 15 so as to engage the edges of the pad 12 to clamp it against the flange 11 and support the central portion of the pad 12 in a dome-like form projecting beyond the plane of the flange.

The other side 16 of the body 13 is flat so 90 that the body is button-like in form, and the side 16 lies a substantial distance within the open end of the band 10. To maintain the block within the band 10 and in firm clamping relation to the pad 12 a flexible disk 17 95 of oiled cardboard or the like is positioned in the open end of the band 10 and in yielding engagement with an annular groove 18 formed in the band.

The pad 12 absorbs the liquid insectifuge 100

from the block 13 and always contains a sufficient amount of the liquid to be applied to a person's skin and since the pad is supported by the block 13 in a dome-like form, it may 5 be rubbed over the skin without causing contact of the metallic band 10 with the skin. The opposite sides of the band 10 provide opposed surfaces by which the device may be grasped to apply the liquid to the skin.

10 The liquid with which the block 13 is impregnated may be of any suitable composition or mixture of different liquids, the preferred mixture containing oil of Pennyroyal and oil of cedar which serve as an insectifuge 15 and alcohol and camphor oil to sooth the insect bites.

The fumes given off by the block at all times serve to drive insects from the immediate vicinity of the device and hence the 20 device is useful about cottages, porches or similar places since several of them may be placed about the room to permeate the air with the fumes given off by the block. When used in this manner the portion of the band 25 10 which projects beyond the retaining disk 17 serves to support the device. Thus the device may be hung in a vertical position on a wall by placing the projecting portion of the band 10 over a nail in the wall.

30 The device may also be positioned on a table and in this position the oiled disk 17 prevents passage of the fumes from the block 13 downwardly to the table and prevents damage to the finish of the table by the fumes.

35 It will be obvious that the manufacturing operations involved in producing the device are exceedingly simple so that the device may be produced very economically, and it should 40 be noted that although a liquid insectifuge is employed it is not necessary to provide a comparatively expensive liquid-tight container. Furthermore, the device is of a form which may be conveniently carried and there is no danger of losing the insectifuge by spilling 45 it from a container.

I claim as my invention:—

1. A device for containing and applying an insectifuge, said device comprising, in combination, a peripheral metallic band 50 having an annular groove adjacent one edge and an inturned flange on the other edge thereof, a pad extending across the aperture defined by said flange and bearing against the inner side of said flange, a body of substantially rigid porous material impregnated with an insectifuge and positioned within said band, said body having one dome-like side engaging said pad so as to support the same in a dome-like form projecting outwardly beyond said flange, and a disk-like member engaging the groove in said band to hold said body in position therein.

2. A device of the character described comprising, in combination, a circular band 55 having an inturned flange at one edge, a pad

extending across the end opening defined by said flange and abutting the inner side of said flange, a circular wooden block impregnated with an insectifuge, said block having one dome-shaped side and being positioned within said band to support said pad in the shape of a dome projecting outwardly beyond said flange, said pad being clamped at its edges between said flange and said block, and means securing said block within said band.

3. A device of the character described comprising, in combination, a body of substantially rigid porous material impregnated with a liquid composed of an insectifuge and a substance which acts to sooth insect bites, a pad having one side bearing against said body whereby to absorb the liquid gradually therefrom, and means holding said pad in position on said body.

4. A device of the character described comprising, in combination, a band, a pad extending across one end of said band, a body positioned within said band and engaging one side of said pad, said body being of a porous material impregnated with an insectifuge, and means within said band to hold said body in position therein, said band projecting beyond said means so that the device may be suspended from a nail or the like.

5. A device for preventing insect bites comprising a body of porous substantially rigid material impregnated with a liquid insectifuge, a pad having one side bearing against said body whereby to absorb the liquid gradually from said body so that the pad may be rubbed over a person's skin, and means holding said pad against said body and providing opposed surfaces by which the device may be grasped.

In testimony whereof, I have hereunto affixed my signature.

JOSEPH F. KASNICKA.
